UNITED STATES PATENT OFFICE.

PAUL SIEVER, OF SOUTH OMAHA, NEBRASKA.

COMBINATION COAT AND HAT RACK FOR THEATER-SEATS AND THE LIKE.

1,161,539.

Specification of Letters Patent. Patented Nov. 23, 1915.

Application filed November 30, 1914. Serial No. 874,725.

To all whom it may concern:

Be it known that I, PAUL SIEVER, a citizen of the United States, residing at South Omaha, in the county of Douglas and State 5 of Nebraska, have invented certain new and useful Improvements in Combination Coat and Hat Racks for Theater-Seats and the like; and I do hereby declare the following to be a full, clear, and exact description of 10 the invention, such as will enable others skilled in the art to which it appertains to make and use the same.

This invention relates to combined coat and hat racks and in particular to combined 15 coat and hat racks adapted for theater seats and the like.

One of the objects of this invention is to provide a compact device adapted especially for theater chairs so arranged as to neatly 20 retain a coat and a hat.

Another object of this invention is to provide a device inexpensive to manufacture, light in structure, and strong and durable in its construction. And another object of 25 this invention is to provide an arrangement whereby one part is braced against the other part.

Other objects and advantages of this invention will be hereinafter more clearly set 30 forth in the specification, pointed out in the claims and illustrated in the accompanying drawings.

Similar characters of reference refer to similar parts throughout the specification 35 and drawings, in which,

Figure 1 is an elevation of the device showing by dotted lines the position of the rack when not in use and substantially its position by full lines when in use. Fig. 2 is 40 a bottom plan view thereof. Fig. 3 is a front edge view thereof. Fig. 4 is a slightly modified form of the hat retaining device removed from the coat retaining device, and Fig. 5 is a detail perspective view of a further modification.

In the drawings 1 is a convenient seat preferably a theater seat having a combined coat and hat rack 2 assembled therebeneath. The combined coat and hat rack is prefer- 50 ably formed of spring steel wire comprising a coat retaining portion 3 and a hat retaining portion 4, portions of the coat retaining member being extended at an angle and bent

into loops 5 and 6, said loops being positioned adjacent the rear corners of the seat 55 through which are passed screw threaded fastening devices 7 to attach the rack to the rear under surface of the seat. One arm of each loop extends rearwardly a short distance when the wire is then bent downwardly at 8. A plurality of coils 9 are formed in the downwardly bent angular portions to allow of the resiliency of action when the coat retaining means is being used, the end coils 10 of which project downwardly 60 and are then curved forwardly into a horizontal portion 11 and 13 respectively which extend forwardly beneath the seat and parallel with the edges of the seat to adjacent the front edge thereof where they terminate 65 in a transverse front structure 12 as clearly shown in Fig. 2 of the drawings. The opposite arms of the loops also extend rearwardly and then inwardly a suitable distance and thence downwardly to a point in 70 a plane with the coat retaining member 3 where they terminate in loops 17 and 22 respectively.

Looped around the front portion 12, as at 14, is one arm 16 of an interbracing member, said arm being extended rearwardly and engaged with the loop 17, the arm 18 of said structure then extending forwardly from the loop 17 and has its outer end provided with a loop 19 which engages the 75 front portion 12, the two arms 16 and 18 being spread apart at their looped ends to form a substantially V-shape structure, the arm 16 being positioned a distance from the side edge of the seat while the arm 18 is 80 positioned adjacent the center of the seat. This structure is placed at one side of the center of the seat and a similar structure is placed on the opposite side of the center of the seat and comprises arms 21 and 24, the 85 outer ends of which are provided with loops 20 and 23 which engage the front member 12, the loop 23 being adjacent the edge of the seat opposite to the loop 14, while the loop 20 is positioned midway between the 90 looped ends 14 and 19, the arms 18 and 21 of the two structures crossing each other. The latter structure composed of arms 21 and 24 is likewise substantially V-shape and has its rear end engaged with the loop 22. 95 These arms 16, 18, 21 and 24 form the inter-

bracing floor and support for the coat when retained within the confines of the coat retaining structure. A horizontal supporting device 25 is then attached to the coat retaining device at the forward corners thereof and looped therearound as plainly shown in Fig. 3 at 26 and 27. The horizontal supporting device 25 then depends as at 28 and 29 in a vertical direction after which the 10 depending portions are bent horizontally and run a short distance in a horizontal direction parallel to the front edge of the chair as plainly shown at 30 and 31 of Fig. 2. It is then gradually curved to the rear 15 as at 32 and 33 to form rearwardly sloping walls 34 and 35 which form the supports to retain the hat, said portions 34 and 35 being curved outwardly in an opposite direction to each other in a manner well known in hat supporting devices of this structure at 20 present in use. The rear portion of the hat supporting device 4 is then caught through the looped portions 17 and 22 previously mentioned, then bent upwardly as at 36 a short distance and then bent downwardly as at 37 as plainly shown in Fig. 3, this portion forming an inverted substantially V-shape guard 15 to prevent the insertion of a coat too far within the coat retaining portion. By this arrangement, the hat supporting device 4 is in a lower position than the coat supporting device 2 but is attached thereto, furthermore, the front portion of the coat supporting device 2 is free from all 25 obstructions to allow of easy passage of a neatly folded coat within the confines of the coat supporting device 2, the coils 9 operating to allow of a degree of resilient action of the wire structure during the insertion of 30 the coat.

In the modified form shown in Fig. 4 the front portion has extensions 38 and 39 as is plainly shown in said Fig. 4 which are extended from the loops 26 and 27, the ends 45 of which are looped as at 40 and 41 and adapted to wrap around the front portion of the wires 24 and 16, this latter modification giving an additional bracing support to the hat retaining device.

50 In the modified form shown in Fig. 5, supporting brackets are formed by bending portions of the wire 8' downwardly and twisting the lower ends of the parallel sections 9' into loops 11', through which extend the side retaining members 3'. When a coat, wrap or package is inserted between the seat and supporting member, the side members will be limited in their downward movement by the loops 11'. This arrangement, as above stated, is adapted primarily for theater seats and the like where the chairs are closely adjacent each other and only a minimum amount of space can be utilized within the confines of the chair seat and which yet is convenient in use and 55 60 65

practical in operation for the reception of coats, hats, wraps and packages of any description not too large to be introduced into the receptacle.

As best shown in Fig. 1 of the drawings, 70 the rack, when not in use, rests against the bottom of the seat, as indicated by dotted lines, the position of the same, when in use, being shown in full lines.

The form herein shown and described is 75 a preferred embodiment of the invention, but the right is expressly reserved to make such alterations and variations therein from time to time as it may be deemed expedient and which will neither depart from the 80 spirit of the invention nor conflict with the scope of the claims.

Having now described my invention what I claim as new and desire to secure by Letters-Patent is:—

85 1. A combined hat and coat retaining device for seats, comprising a wire frame work, a portion of said wire being bent upon itself to form loops, one arm of each loop being formed into a coiled portion, the outer coil of each coil section terminating in a downwardly and forwardly extending section to form side members parallel with the side edges of the seat, said side members terminating in a transverse front section parallel with the front edge of the seat, the opposite arm of each loop member being extended inwardly and downwardly, the free ends thereof being formed into loops, means engaging said first loops to attach the retaining device to the seat, interbracing members extending from said front section to said last mentioned loops, a hat retaining device comprising a pair of curved side members extending from the front to 90 the rear edge of the first frame, the forward ends of said side members having loops engaging the side members of the first structure adjacent their forward ends, the integral rear portion of said curved 95 side members engaging said extended loops, that portion between the last mentioned loops being bent to substantially U-shape to form a guard.

100 105 110 115 120 125 130 2. A combined hat and coat retaining device for seats comprising a wire frame work, a portion of said wire being bent upon itself to form loops, means to engage the loops with the seat, one arm of each loop being formed into a coiled portion and the opposite arms into depending members having loops at their ends, said coiled portions terminating in downwardly and forwardly extending sections forming side members, said side members terminating in a transverse front section, interbracing members extending from said front section to the loops of said depending members, a pair of curved side members integral at one end, said side members having their forward

ends secured to the side members and their rear ends to the loops of the depending members of the first frame, and means to limit the vertical movement of the retaining device.

5 In testimony whereof I have signed my

name to this specification in the presence of two subscribing witnesses.

PAUL SIEVER.
